UNITED STATES PATENT OFFICE.

CHARLES E. ECKERLE, OF BIRMINGHAM, ALABAMA.

HYDROCARBON-OIL BURNER.

Application filed September 29, 1922. Serial No. 591,261.

To all whom it may concern:

Be it known that I, CHARLES E. ECKERLE, a citizen of the United States of America, residing at Birmingham, in the county of 5 Jefferson and State of Alabama, have invented certain new and useful Improvements in Hydrocarbon-Oil Burners, of which the following is a specification.

My invention relates to hydrocarbon oil 10 burners of the type adapted to burn kerosene and the lighter grades of fuel oil.

The objects of my invention are to improve the operation of the burner by elongating the mixing passages through which 15 the air and oil flow to the burner chamber, such passage being effectually protected from the direct action of the flame to avoid overheating and back firing.

A further novel feature of my invention 20 relates to the arrangement of the vaporizer relative to the burner ports to protect the former from excessive heat and reduce to a minimum the trouble of carbonization.

A further novel feature of my invention 25 relates to the vaporizer and to means therein for effecting such a flow of the oil as will result in a minimum of carbonization while insuring a vaporization which is rapid and ample in volume so as to enable the burner 30 to come rapidly into service.

A further feature relates to the provision of means to catch and collect the carbon which are readily removable and replaceable so that the burner can be kept in operating 35 condition with small expense and but slight trouble.

My invention further comprises the novel features of construction and arrangements 40 of parts, which in their preferred embodiment only are illustrated in the accompanying drawings, in which:

Fig. 1 is a side elevation of my improved burner complete.

Fig. 2 is a sectional view taken on the 45 line 2—2 of Fig. 4.

Fig. 3 is an enlarged cross-sectional view through the vaporizer.

Fig. 4 is a cross-sectional view taken on the line 4—4 of Fig. 2.

Fig. 5 is a plan view of Fig. 1.

Fig. 6 is a cross-sectional view of a modified form of vaporizer.

Similar reference numerals refer to similar parts throughout the drawings.

In the preferred embodiment of my invention illustrated, the burner comprises a base casting having legs 1 terminating at their upper ends in seats 2 extending along each side of the burner and having a lip 3 along their outer edges and a wall 4 rising from their inner edges. The wall 4 on one side joins an overhead wall 5 and on the other side joins a concave wall 6. In the center of the top wall 5 I cast bosses 7, each having a threaded opening tapped therein 55 to receive the screw 8, by means of which the outer burner shell is mounted in assembled position on the base. This burner shell comprises a convex top portion 9 slightly less in length than the base and provided at each end with down-turned flanges 10 which are forced between the end flanges 11 on the base, it being noted that on each end of the curved wall 6 is provided a shoulder 12 symmetrical with the 60 wall 5 on which the flange 10 rests. This flange 10 also extends down along the side walls 13 of the burner shell which are provided to rest on the seats 2, fitting snugly 65 between the flanges 3 with the shell flanges 80 10 engaging the walls 4 of the base. Along one corner of the burner shell opposite the curved wall 6 is provided an indentation in the casting forming an oil groove 14 adapted to receive the priming oil for heating the 85 vaporizer 15. The vaporizer is shown mounted in end walls 16 cast integral with the burner shell and disposed at each end of the groove 14. The vaporizer is preferably held in place by metal straps 17 which at 90 one end are attached to the shell by the adjacent screw 8 and at the other end, after being passed over the vaporizer, are connected to the outer side of the end walls 16 by screws 18. This brings the vaporizer to 95 one side of the burner which is provided with a series of burner slits 19 (see Fig. 5) extending adjacent to the groove 14 to a point adjacent to the opposite side of the top wall 9. In addition to this I provide 100 burner slots 20 in each side wall 13, it being noted that the vaporizer in being offset inwardly from the burner slits adjacent to it will not receive the direct action of the flame and will not tend to become too highly heated.

I cast integral with the base a mixing chamber in tubular form having a reverse

bend, the chamber at its lower end is connected to a cross web 21 connected to front legs 1 of the burner and extending upwardly approximately to the level of the seats 2. On this wall the mixing chamber comprises first a chamber 22 having a bottom opening 23 for the admission of air and having a wall 24 set opposite the web 21. The wall 21 is provided with an opening 25 to receive with a snug fit the burner nozzle 26, and in the wall 25 opposite to and in alignment with the opening 25 is a corresponding opening 27 through which the jet of vaporized fuel with the entrained air enters the lower mixing chamber 28. Thence the mixture flows through the bend 29 and through the upper mixing chamber 30 which opens through a port 31 in the top center of the wall 5 of the base casting. It will be observed that the lower mixing chamber 28 has its bottom dropped to form a collecting recess 32 for the oil which condenses and runs back when the burner is started up. This oil however vaporizes when the burner reaches a sufficient heat.

The hydrocarbon oil, preferably kerosene, is supplied through a duct 33 to a plug 34 screwed into the tubular vaporizer shell 15. This plug is provided with a duct 35 registering with the duct 33 and enlarged at its inner end 36 to form a guide for the stem 37 on a disk 38 which fits snugly with a small clearance in the bore of the tube 15. The stem 37 in like manner fits with a close clearance in the duct 36 and tends to restrict the flow of the oil therethrough. I indent the tube 15 at several points, as indicated at 39, so as to form shoulders to limit the inward movement of a cylinder 40 of carbon, or any like suitable material, which is introduced into the vaporizer in front of the disk 38. The vaporizer is screwed into a T-fitting 41 with its inner end registering with the inner open end of a shell 42 and closed at its outer end and threaded into the T-fitting with a wrench grip 43. The shell 42 is provided circumferentially with a series of ports 44 and has mounted therein a wire mesh sleeve 45 closed at its inner end and adapted to receive and collect the carbon formed in the vaporizer. It will be observed that the shell is surrounded between its ends with a clearance chamber 46 so that the gas escaping through the ports 44 surrounding the sleeve, as indicated by the arrows, passes downwardly through the fitting connection 47 and enters the burner nozzle 26, whence it is discharged under control of the needle valve 48 into the chamber 22.

I show in Fig. 6 a modification of my vaporizer wherein the carbon cylinder 40^a is provided with an enlarged shoulder 38^a corresponding in diameter to the metal disk 38 so as to take the place of the latter.

Under such conditions the enlarged inner port 36 in the plug can be eliminated and the restricted duct 35 carried all the way through the plug. This construction is simpler and less expensive, especially where the molded carbon shapes are available.

Having assembled the parts in the manner described, the operation is as follows.

The oil flowing under suitable pressure through the ducts 33 and 35 is restricted by the stem 37 and in small volume passes into the vaporizer in front of the disk 38 or shoulder 38^a. The disk 38 will drop closer to the bottom of the vaporizer shell 15 than to any other part and will allow only a very restricted flow of oil to escape about it like an annulus, which condition is preserved as the oil flows lengthwise about the carbon cylinder 40. As a result the oil is maintained in a very thin substantially annular space and is readily vaporized, the oil vapors flowing through the screen 45 and escaping through the sleeve ports 44, and flowing down through the tube 47 to the burner nozzle 26, thence they escape as a jet under control of the needle valve 48 into the mixing chamber 22. In traversing this chamber the gas jet entrains air and the mixed gas and air flow through port 27 into the lower mixing chamber and thence by the reverse bend through the upper mixing chamber and into the distributing chamber between the walls 4 and 5 on one side and 9 and 13 on the other. In this chamber the gas escapes through the slots 19 and 20 and burns above and on each side of the burner to afford an effective well distributed flame. When starting the burner, the groove 14 is filled with priming oil and this is ignited to heat the vaporizer until the burner starts. As the oil tends to vaporize during the starting up of the burner it will condense and collect in the pocket 32 whence it will be later vaporized as the burner heats up. The burner will not back fire and will give continuous uniform heat with a relatively low pressure of oil and with very little trouble from carbonization, which, when it occurs, can be readily corrected by unscrewing the sleeve 42 and cleaning the plug and its wire screen 45.

Though I have described with great particularity the details of the embodiment of the invention herein shown, it is not to be construed that I am limited thereto as changes in arrangement and substitution of equivalents may be made by those skilled in the art without departing from the invention as defined in the appended claims.

Having thus described my invention, what I claim as new and desire to secure by Letters Patent, is:—

1. In a burner, an arched hollow shell, a mixing chamber opening into the space within the shell and disposed within the

arch of the shell and having a reverse bend therein to elongate it, external burner slots in the shell, a vaporizer, and means to admit a regulable volume of gas and air into said mixing chamber.

2. A burner in accordance with claim 1, in which said reverse bend of the mixing chamber is spaced from and protected from reflected heat by the side walls of the burner arch.

3. A burner in accordance with claim 1, in which the burner slots are arranged along the sides and top of the shell, an oil groove being provided along one corner of the shell, and a vaporizer mounted longitudinally over said groove and protected thereby from direct contact with the flames.

4. In a burner, an arched base casting having integral therewith and disposed within the arch a mixing passage formed with a reverse bend and opening centrally through the top of the base casting, means to introduce air and gas into the intake end of said passage, a vaporizer to supply the gas, and an outer arched burner jacket seated on the base casting and forming an arched gas chamber with an oil groove un-

der the vaporizer, there being burner slots in the outer sides and top of said jacket.

5. A burner in accordance with claim 4, in which the vaporizer is mounted at one side in position to avoid direct contact from flames from the adjacent side and top burner slots.

6. In a burner, an elongated arched hollow base casting having a reverse bend mixing passage cast thereunder in spaced relation to its side walls, said passage having a bottom air inlet at its intake end and having its discharge end opening upwardly through the middle of the casting, a jacket mounted on the base casting with its intermediate portion spaced therefrom and having burner slots in its sides and top, means to mount a vaporizer along one corner of said jacket, and valve controlled means to discharge gas from said vaporizer in the form of a jet flowing above said air inlet into said mixing passage.

In testimony whereof I affix my signature.

CHARLES E. ECKERLE.
